UNITED STATES PATENT OFFICE.

NORMAN SELFE, OF SIDNEY, NEW SOUTH WALES, ASSIGNOR OF ONE-HALF
TO HUDSON BROTHERS, OF SAME PLACE.

APPARATUS FOR COMPRESSION AND EXPANSION OF AIR, GASES, AND VAPORS FOR REFRIGERATING AND OTHER PURPOSES.

SPECIFICATION forming part of Letters Patent No. 250,586, dated December 6, 1881.

Application filed September 21, 1881. (No model.) Patented in New South Wales April 2, 1880.

To all whom it may concern:

Be it known that I, NORMAN SELFE, of Sidney, in the colony of New South Wales, have invented certain new and useful Improvements 5 in Apparatus for Compression and Expansion of Air, Gases, and Vapors for Refrigerating and other Purposes, of which the following is a specification.

My said improvements are embraced in Letters Patent No. 812, dated April 2, 1880, granted to me by the government of New South Wales.

The invention relates more particularly to refrigerating apparatus in which air or gases 10 are compressed by successive stages or operations, and cooled between the successive stages or operations by being passed through heat-exchangers or surface condensers or coolers, whereby the heat rendered sensible at each 15 stage of the compression is abstracted before the air or gas is subjected to the next stage of compression. The heat rendered sensible at each stage of compression can thus be imparted to other substances and utilized instead of 20 being carried away by condensing-water, and the air or gas can be highly compressed without the inconvenience of the great heat and loss of power attending the use of ordinary 25 compressors.

The invention consists in the combination, with a compressor and an engine or prime-mover for working the same, of a supplementary engine operated by vapor generated from 30 a volatile liquid by the heat rendered sensible in the compressor itself. Ether or other volatile liquid may be passed through the aforesaid heat-exchangers or surface-condensers, and the heat rendered sensible by the compression of air or gas will generate a vapor, 35 which, being applied to the piston of the supplementary engine, will operate the same and furnish a part of the power necessary to work the machine, and will reduce the amount of condensing-water necessary to remove the remainder of the heat rendered sensible by compression.

The invention also consists in the combination, with the compressor and its operating-

engine or prime mover, of both the supplementary engine operated by vapor generated from a volatile liquid by the heat rendered sensible by compression, and a supplementary engine or engines operated by the expansive force of air or vapor compressed by the aforesaid compressor, whereby I provide for the 55 very economical operation of the apparatus.

In the accompanying drawings, Figure 1 represents a partly-sectional plan of a refrigerating room and apparatus constructed and arranged according to my invention; and Fig. 60 2 represents a similar view of an apparatus of modified form.

Referring first to Fig. 1, A designates a cooling room or chamber, which may be constructed in any suitable manner, and is provided with 65 a surrounding air-space, A', and with double doors A² A³.

B designates the cylinder of a steam-engine, which constitutes the prime mover of the machine or apparatus, and may be of any suitable construction. B' designates the cylinder of a compressor, or rather a compressing-cylinder, which may likewise be of any suitable construction; and B² designates a second compressing-cylinder, which is of smaller diameter 75 than the cylinder B'.

C designates the cylinder of an engine which is to be worked by the expansion of compressed air or gas, and C' designates the cylinder of a similar engine, but larger in capacity than the 80 cylinder C.

D designates the cylinder of an engine to be operated by the pressure of a vapor generated from a volatile liquid—such as ammonia or ether—by the heat rendered sensible by compression.

E F G H designate what I term “heat-exchangers,” each of which comprises a shell or body, with a small chamber at each end, and tubes extending from end to end thereof, they 90 being constructed like any ordinary surface-condenser. The pistons of the several cylinders B B' C' are all connected to a common piston-rod, I, so as to move simultaneously, and the pistons of the several cylinders B² D C are 95 all connected to another piston-rod, I'.

J J' designate pitman or connecting rods, whereby the two piston-rods I I' are connected with a crank-shaft, K, upon which are fly-wheels K' K', and which is adapted to rotate in suitable bearings.

I would here remark that the purpose of the steam-engine B is to drive both the compressing-pumps or compressors B' B²; but its power is supplemented by the power generated in the supplementary vapor-engine D and the supplementary air-engines C C', and hence its capacity and its consumption of steam need not be as great as would otherwise be required.

I will now describe the several connecting air-pipes of the apparatus.

a designates a pipe leading from the cooling-room A to the compressor-cylinder B', and constituting the suction-pipe therefor.

b designates the discharge-pipe of the compressor-cylinder B', through which the air is conducted into the body of the heat-exchanger E, from which it passes through a pipe, c, to the second compressor-cylinder, B². From the compressor-cylinder B² the fully-compressed air is conducted through a pipe, d, to and through the tubes of the second heat-exchanger, F, from which it passes through a pipe, e, to and through the tubes of the third heat-exchanger, G, from which it issues through a pipe, f. The heat-exchanger G is in fact a condenser, and has proper inlet and outlet pipes, G' G², for water or other cooling-fluid. The air, which is now deprived of the greater part of the heat rendered sensible by compression, passes through the pipe f to the engine-cylinder C, wherein it expands and produces a certain amount of power, and from the cylinder C it passes through the pipe g to and through the heat-exchanger H, and thence through a pipe, h, to the larger cylinder, C', wherein it still further expands and produces more power. From the cylinder C' the air passes through a pipe, i, wherein is a chamber, i', to the cooling-room A.

I will now describe the circulating-pipes for volatile liquid and the vapor generated therefrom.

j designates a pipe for volatile liquid, leading from the fourth heat-exchanger, H, and having connected with it a reservoir, j', for volatile liquid, and a pump, j², for producing the circulation thereof. (The pump here represented is of the rotary class.) The volatile liquid passes through the pipe j, to and through the tubes of the first heat-exchanger, E, wherein it is raised in temperature and partly volatilized or vaporized; thence through a pipe, k, to and through the body of the second heat-exchanger, F, wherein its vaporization is completed; thence the vapor passes by a pipe, l, to the cylinder D, wherein it does its work, and from which it escapes through a pipe, m, to and through the tubes of the fourth heat-exchanger, H, wherein it is cooled and liquefied.

The operation of the apparatus is as follows: The engine B being set in operation, the sev-

eral pistons will be set in motion and air will be drawn through the pipe a into the cylinder B'. This air on being compressed will be reduced in volume and increased in temperature through some of the latent heat becoming sensible, and on being discharged through the pipe b into the heat-exchanger E this air will impart some of its heat through the metallic surfaces thereof and become cooler, and at the same time it will deposit a portion of any moisture it may contain on the metallic surfaces. The air will then pass through the pipe c into the compressor-cylinder B², where it will be further reduced in volume and again increased in temperature, after which it will pass through the pipe d into the heat-exchanger F, where it will part with more heat and deposit more moisture. The air then passes through the pipe e to and through the tubes of the condenser G, where it deposits more moisture and is further cooled, if necessary, after which it passes through the pipe f to the cylinder C, where it will give out power by its expansion. The air passes from the cylinder C by the pipe g to and through the body of the heat-exchanger H, and by the pipe h to the cylinder C', in which it is again expanded and gives out power, being still further reduced in temperature and increased in volume. The air passes from the cylinder C' by the pipe i into the chamber A or air-space A', where it takes up heat from the articles to be kept cold and then re-enters the apparatus through the pipe a, as before.

While the above-described operation is being performed ether or some other volatile liquid is pumped by means of the pump j² into and through the tubes of the heat-exchanger E, where it is vaporized by heat abstracted from the air, after which it passes through the pipe k to and through the body of the heat-exchanger F. From the heat-exchanger F the vapor passes by a pipe, l, to the cylinder D, wherein it performs its work by expansion, and from which it passes by the pipe m to and through the tubes of the heat-exchanger H, where its heat is abstracted by the air and it is liquefied. The heat thus taken up by the ether from the compressed air will render less water necessary in the condenser G, and will give out power in the engine D and assist in driving the whole machine. When the chamber A is reduced to the desired temperature the pipes a and i may be disconnected from the chamber itself and connected with the jacket A', to prevent the infiltration of heated air and keep the chamber cool without changing the air therein.

Fig. 2 represents another form of similar apparatus, but with one compressing-pump and one expansion-engine for the air, and one engine for the secondary vapor, details being omitted for simplicity.

A is the cylinder of a pump for compressing air.

B is the cylinder of an engine worked by compressed air.

C is the cylinder of a vapor-engine.

- D is a surface condenser or vaporizer fitted with tubes or other metallic surfaces for transmitting heat. 55
 E is a surface-condenser similar to D.
 5 F is a vapor-condenser similar to D.
 G is a crank-shaft connected to the piston-
 rods of A, B, and C by means of a pitman or
 connecting rod, G', or other suitable means.
 a is a pipe supplying the air or gas to be com-
 pressed to cylinder A.
 10 b is a pipe leading compressed air or gas
 from compressor A, and forming part of va-
 porer D.
 c is a continuation of pipe b, forming part of
 15 surface condeuser or exchanger E.
 d is a further continuation of pipe b, con-
 veying compressed air or gas to expansion-en-
 gine B.
 20 e is the exhaust-pipe of expansion-engine B,
 leading to vapor-condenser F.
 f is a continuation of e, being portion of con-
 denser or exchanger F.
 h h are stop-cocks or traps for removing de-
 posited water.
 25 k k are pipes to h.
 l, Fig. 2, is a pump for removing volatile liquid
 from condenser F to condenser D in the direc-
 tion shown by the arrows.
 m m are gas-pipes conveying vapor under
 30 pressure to gas or vapor engine C.
 n n is the exbaust-pipe to engine C, convey-
 ing vapor under reduced pressure to F.
 o and p are pipes for the inlet and outlet of
 condensing-water to surface-condenser E.
 35 g is a pipe leading off cooled air to where it
 is required.
 On the machine thus described being set in
 motion through power applied to the crank-
 shaft G, air is admitted by pipe d and com-
 pressed by the piston of compressor A, when
 40 its latent heat is rendered sensible and is com-
 municated to the metal of the compressor and
 exhaust-pipe b, by which it leaves. The com-
 pressed air then passes through pipe e into
 45 surface-condenser E, where it is cooled by com-
 ing in indirect contact with the circulating
 water. The compressed air is then passed to
 expansion-engine B, where it exerts its power
 upon the piston, performs work, parts with
 50 heat, and then exhausts by pipe e into pipe f,
 which constitutes part of vapor-condenser F,
 at the same time becoming cold from the re-
 expansion or released pressure. The cold air
 then passes by pipe g to where it is required,
- and any moisture deposited is drawn off at h and 55
 k. While the above-described operations are
 being performed the pump l, Fig. 2, draws liquid
 either from condenser F and discharges it into
 condenser D, where, in coming in contact with
 pump A and pipe b, it is converted into vapor 60
 under pressure. The vapor is then delivered
 by pipe m to the vapor or gas engine C, where
 it expands against the piston, performs work,
 becomes reduced in temperature, and then
 passes by exhaust-pipe n into condenser F, 65
 where it is cooled by contact with the pipe f,
 containing cold air, to be again liquefied, when
 it is again drawn off by pump l, Fig. 2, and the
 operation is continuous.
 In either of the foregoing arrangements the 70
 compression and expansion cylinders can be
 fitted with jackets for the circulation of vola-
 tile material or water, for the purpose of tak-
 ing up or abstracting heat from the air, and
 additional exchangers can be applied on pipes 75
 d, if desired.
- What I claim as my invention, and desire to
 secure by Letters Patent, is—
1. The combination, with a compressor and
 an engine or prime mover for working the 80
 same, of a supplementary engine operated by
 vapor generated from a volatile liquid by the
 heat rendered sensible in the compressor it-
 self, substantially as and for the purpose speci-
 fied. 85
2. The combination, with a compressor and
 an engine or prime mover for working the
 same, of a supplementary engine operated by
 vapor generated from a volatile liquid by the
 heat of the compressed air or gas, and one or 90
 more supplementary engines operated by the
 expansion of the compressed air or gas, sub-
 stantially as and for the purpose specified.
3. The combination, in an air-compressing
 apparatus, of the compressing-cylinders B' B², 95
 of different sizes, the steam-engine B, the sup-
 plementary vapor-engine D, the supplement-
 ary air-engines C C', of different sizes, the heat-
 exchangers E F G H, and the connecting-pipes
 for air and volatile liquid and vapor, all ar- 100
 ranged and operating substantially as speci-
 fied.

In testimony whereof I hereunto sign my
 name this 11th day of June, 1881.

NORMAN SELFE.
